METAL COATING MACHINE

William F. Lohrman, New Castle, Pa.

Application August 3, 1940, Serial No. 350,949

1 Claim. (Cl. 91—12.7)

This invention relates to metal coating machines and more particularly to those which coat sheet metal with tin, although not limited thereto.

In providing sheet metal with heavy metallic coatings considerable difficulty is experienced in obtaining the desired results. This is particularly true in providing metallic sheets with a heavy coating of tin, for example, of the order of two and one-half pounds per base box (112 sheets) which is known in the trade as "charcoal tin plate." In the commercial manufacture of this produce redipping in molten tin was resorted to in order to attain the desired weight of coating. More recently the redipping step was eliminated and the exit rolls of the tin pot were made to run in shallow pans which were filled with molten tin. These pans were filled with molten tin by manual dipping from the main body of the molten tin and the pouring of the same into the shallow pans. When the metal was dipped by hand it was not possible to maintain a constant level thereby effecting irregularity in the amount of coating applied to the sheet metal. In addition, it was not possible to provide the shallow pans with a supply of pure tin as in the tinning operation considerable impurities, commonly referred to as "scruff," are formed and this floats on the surface of the molten tin to be picked up by the manual dipper, thereby resulting in the contamination of the tin supply in the shallow pans with the consequent result that the scruff would settle on the coating.

It is an object of the present invention to provide sheet metal with even heavy metallic coatings of a relatively pure metal.

Another object is to apply to the exit rolls of a tin pot a constant quantity of relatively pure tin.

Still another object is the attainment of the foregoing in a simple and inexpensive manner.

The invention, then, comprises the features hereinafter fully described and as particularly pointed out in the claims, the following description, and the annexed drawings setting forth in detail a certain illustrative embodiment of the invention, this being indicative of but one of the number of ways in which the principles of the invention may be employed.

In said drawings:

Figure 1 is a vertical elevation of the machine of the present invention;

Figure 2 is a vertical elevation taken at 90° from the view of Figure 1;

Figure 3 is an enlarged detail;

Figure 4 is a fragmentary view of a detail, part of which is shown in section; and

Figure 5 is a fragmentary schematic elevation.

Referring more particularly to the drawings,

the numeral 2 generally designates a tin pot of more or less conventional design except for the provision of the apparatus of the present invention which will be referred to hereinafter. This conventional tin pot 2 is provided adjacent its bottom with a supply 4 of relatively pure tin maintained at the desired level. Disposed within the tin pot 2 is a series of suitably driven pairs of rolls 6 which advance the sheet metal to be coated through the supply 4 of tin and upwardly out of the tin pot 2. Therefore, some of the rolls 6 are maintained within the supply 4 of molten tin whereas the remainder thereof are disposed above the same at suitable elevations progressively out of the tin pot 2. The exit rolls of the conventional tin pot 2 are conventional in design and are designated herein at 8. Disposed beneath each of the pairs of exit rolls 8 is a shallow pan 10, communication therebetween being provided by means of a connecting trough 12. Adjacent one end of one of the pans 10 there is provided a funnel 14 formerly through which molten tin was supplied by means of a manually operated dipper.

According to the teachings of the present invention there is provided in outboard relationship with respect to the pans 10, and at approximately the same horizontal elevation as the funnel 14, a box 16 from which there is supplied by means of a connecting pipe 18 molten tin at a constant rate of feed. In order to accomplish this end the shaft 20 of one of the exit rolls 8 is provided with an outboard extension to which there is connected a sprocket 22. The shaft 24 of one of the rolls 6 which is maintained below the level of the tin supply 4 is provided with a corresponding outboard extension to which there is secured a sprocket 26. The sprockets 22 and 26 are connected by means of a suitable drive chain 28. At suitable intervals there is connected to the drive chain 28 a series of suitably formed buckets 30 which are so constructed and arranged as to provide for the reception of the molten tin, elevation thereof to a point above the box 16 and the dumping thereof into the said box. It will thus be seen that the proper correlated sizes and number of buckets 30 will result in the transfer to the box 16 of a supply of molten tin which will be sufficient to maintain a level thereof within the pans 10 which will result in the application by the exit rolls 8 of a coating of sufficient evenness and heaviness. In order to prevent a superfluous supply of molten tin to the pans 10 one of the latter is provided with an overflow notch 32 from which the molten tin may drop downwardly into the main supply 4 of molten tin in the bottom of the tin pot.

Referring more particularly to Figure 2, it will be noted that there is provided a skimmer box

34 which encompasses the sprocket 26 and the drive chain 28 at positions both above and below the level of the supply 4 of molten tin. This results in the prevention of the scruff from forming at a point where the buckets 30 leave the molten tin. Consequently the tin supply to the buckets 30 is relatively pure.

While I have shown and described one specific embodiment of the present invention, it will be seen that I do not wish to be limited exactly thereto, since various modifications may be made without departing from the scope of the invention, as defined by the following claim.

I claim:

A machine for applying a metal coating to metal sheets and the like, comprising a pot containing a molten metal bath, a pair of rolls hori-

zontally disposed above the level of the molten metal bath, at least one pan extending beneath said rolls, said pan being adapted to contain sufficient molten metal to immerse the lower portion 5 of the periphery of the rolls therein, a driven endless belt extending from beneath the level of the molten metal bath into proximity with respect to said pan, at least one bucket carried by said endless belt and constructed and arranged 10 to transfer molten metal from the bath into said pan, means for maintaining substantially constant the level of molten metal in said pan, and a wall isolating that area of the surface of the molten metal bath through which said bucket operates from the remainder thereof.

WILLIAM P. LOHRMAN.
